(57) **CLAIM**

The ornamental design for product packaging, as shown and described.

DESCRIPTION

FIG. 1 is a perspective view of the product packaging with self-locking ties showing my new design; FIG. 2 is a top view of the product packaging shown in FIG. 1;

FIG. 3 is a bottom view of the product packaging shown in FIG. 1;

FIG. 4 is a first side view of the product packaging shown in FIG. 1;

FIG. 5 is a second side view of the product packaging shown in FIG. 1;

FIG. 6 is a first end view of the product packaging shown in FIG. 1; and,

FIG. 7 is a second end view of the product packaging shown in FIG. 1.

Broken lines are used in the drawings to illustrate features that form no part of the claimed design.
